DESIGN FOR A RIBBON

Oscar Lion, New York, N. Y.

Application July 27, 1936, Serial No. 64,073

Term of patent 3½ years

To all whom it may concern:

Be it known that I, Oscar Lion, a citizen of the United States of America, residing in Manhattan, county of New York, and State of New York, have invented a new, original, and ornamental Design for a Ribbon, of which the following is a specification, reference being had to the accompanying drawing, forming part thereof, wherein,

The figure is a plan view of a piece of ribbon showing my new design.

The characteristic feature of my chamois chiffon ribbon resides in the broad delustered center having gauze stripes on either side and a lustrous border.

I claim:

The ornamental design for a ribbon, substantially as shown, and described.

OSCAR LION.
